HYDROXY ACETAL COMPOUNDS AND THEIR
PREPARATION

David I. Weisblat, Galesburg, and Barney J. Magerlein, Kalamazoo, Mich., assignors to The Upjohn Company, Kalamazoo, Mich., a corporation of Michigan

No Drawing. Application May 8, 1952,
Serial No. 286,821

13 Claims. (Cl. 260—470)

1

This invention relates to certain hydroxy acetal esters and acids and to a method for their preparation. This application is a continuation-in-part of application Serial No. 63,453, filed December 3, 1948.

Hydroxy acetal compounds of the invention which can be prepared by the method given herein, sometimes referred to herein as N-(3,3-di-alkoxy-2-hydroxypropyl)-N-(arylsulfonyl)-p-aminobenzoate compounds, have the generic formula

N-(3,3-di-alkoxy-2-hydroxypropyl)-N-(arylsulfonyl)-p-aminobenzoate compounds

wherein R' is a member of the group consisting of hydrogen and the alkyl radicals and n is a member of the group consisting of zero and the positive integers 1 to 7, inclusive. They thus include N-substitution products of p-aminobenzoic acid, of p-aminobenzoyl-glutamic acid, of p-aminobenzoyl-glutamyl-glutamic acids having up to seven glutamic acid residues in the molecule, and of their esters, the N-substituent being in each case a 3,3-di-alkoxy-2-hydroxypropyl radical.

In the structural formulae given herein and in the appended claims aromatic nuclei are represented by one or more simple hexagons. In the naming of compounds having the generic formula given and of other compounds mentioned herein wherein both a glutamic acid residue and a p-aminobenzoic acid residue are included in the molecule, the nitrogen atom of the glutamic acid residue is, for convenience, herein referred to by the symbol "N" and the nitrogen atom of the p-aminobenzoic acid residue is referred to by the symbol "N." As indicated by the generic formula, compounds used in or prepared by the process of the invention which contain more than one glutamic acid or ester residue are those wherein only the gamma-carboxyl groups are involved in the peptide linkages. Preferred compounds used in or prepared by the method of the invention are those wherein n of the generic formula given, and in those given subsequently, repre-

2

sents zero or the integer 1, i. e. those containing either no glutamic acid or ester residue or only one glutamic acid or ester residue, and the method will be described with particular reference thereto.

Compounds having the generic formula given above are of particular value as intermediates in the preparation of compounds similar to or identical with certain naturally occurring compounds of the folic acid group. Thus, as described in the parent application referred to and

in concurrently filed co-pending application Serial No. 286,822, the hydroxy acetal esters or acids (III) of the present invention can be oxidized readily to form the corresponding keto acetal esters or acids, respectively, and the latter can be condensed readily with 2,4,5 triaminom-6-hydroxypyrimidine to form alkyl N-((2-amino-4-hydroxy-6-pteridyl)-methyl)-p-aminobenzoates or dialkyl N'-((2-amino-4-hydroxy-6-pteridyl)-methyl)-N-(arylsulfonyl)-p-aminobenzoyl-glutamates, or the free acids, depending upon the particular hydroxy acetal started with. These latter compounds can, in turn, by hydrolysis of the ester group with alkalies in the case of the esters, and upon removal of the arylsulfonyl radical, e. g. with hydrogen bromide and a bromine acceptor in an aliphatic acid medium, be converted directly to pteroic acid or to a pteroyl-glutamic acid which latter compound appears to be identical with the "L. casei factor" or vitamin B₁₂ obtained from liver. The order of the hydrolysis step and the splitting of the arylsulfonyl radical can be reversed, if desired.

Compounds having the generic formulae given in which the glutamic acid residues have the 1(+) configuration are of particular interest because of the existence of glutamic acid residues having the same configuration in folic acid compounds isolated from natural sources. The method of the invention and the intermediate compounds to be described are, however, not

limited as to the configuration of the glutamic acid residues involved.

The process of the invention, as illustrated in the accompanying reaction chart wherein the formulae of the compounds given are numbered to correspond with the following description and wherein *n* and *R'* have the values given previously, comprises the step of reacting a 2,3-oxidopropanal dialkyl acetal (I) with an N-(arylsulfonyl)-p-aminobenzoate ester (II) to give compounds of the invention (III) which are alkyl esters, i. e. wherein *R'* of the generic formula (III) is an alkyl radical. The corresponding acids, i. e. compounds wherein *R'* of the generic formula (III) is hydrogen, can be prepared by careful hydrolysis of the esters with alkalies and subsequent acidification of the alkaline mixture.

Certain of the N-(arylsulfonyl)-p-aminobenzoate esters (II) are described and claimed in co-pending application Serial No. 41,888, filed July 31, 1948. They can be prepared readily, as described in the co-pending application just mentioned, by reacting an arylsulfonyl halide with an alkyl ester of p-aminobenzoic acid, of p-aminobenzoyl-glutamic acid, or of a p-aminobenzoyl-glutamyl-glutamic acid having up to seven glutamic acid residues in the molecule.

Dialkyl acetals of 1,2-oxidopropanal which can be used in the process include the dimethyl, diethyl, di-n-propyl, di-iso-propyl, dibutyl, diamyl and other dialkyl acetals. As a matter of convenience and availability dialkyl acetals wherein the alkyl radicals each contain less than 8 carbon atoms are preferred, although others can be used, if desired. It is apparent that the nature of the alkyl groups in the hydroxy acetal radical of the compounds of the invention are determined by the particular 1,2-oxidopropanal dialkyl acetal (I) used in carrying out the reaction and that the alkyl esters which are formed are determined by the particular N-(arylsulfonyl)-p-aminobenzoate esters (II) used.

Esters which can be used as starting compounds in the process, with the production of the corresponding esters (III) of the invention, include the methyl, ethyl, n-propyl, iso-propyl, butyl, amyl, hexyl, nonyl and other alkyl esters. As a matter of convenience, lower alkyl esters containing less than about 8 carbon atoms in the alkyl ester radicals are preferably used in the process, although insofar as is known any alkyl ester can be used.

Although starting compounds containing substantially any arylsulfonyl radical can be used

in the process of the invention and in the preparation of the corresponding arylsulfonyl intermediates and final products, the preferred starting materials and intermediate products are those containing the p-toluene-sulfonyl radical due to the ready availability of the p-toluene-sulfonyl halides and to the generally crystalline nature of the p-toluenesulfonyl derivatives of compounds with which the present invention is concerned. The invention is, however, not limited to compounds containing the p-toluenesulfonyl radical and compounds containing other arylsulfonyl radicals, such as the benzenesulfonyl, o-toluenesulfonyl, naphthalenesulfonyl, methyl-naphthalenesulfonyl radicals and others, can be used, if desired.

It should also be mentioned that compounds

containing arylsulfonyl radicals having non-hydrocarbon substituents can be used in the process and the corresponding intermediates and final products prepared, provided only that the substituent is non-reactive under the reaction conditions. Such non-reactive substituents include chlorine, bromine, and the methoxy, phenoxy, nitro and similar radicals. It should be mentioned further that, although the present invention is concerned primarily with compounds wherein the sulfonyl radical is an arylsulfonyl radical, the process can also be carried out and the corresponding products prepared using starting materials containing alkylsulfonyl, aralkylsulfonyl, or cycloalkylsulfonyl radicals, such as the methanesulfonyl, ethanesulfonyl, cyclohexylsulfonyl, and phenylmethanesulfonyl radicals.

The reaction of a dialkyl acetal of 2,3-oxidopropanal with an N-(arylsulfonyl)-p-aminobenzoate ester can be carried out readily by heating the substances together, preferably with the addition of a catalytic proportion of pyridine or other tertiary amine. Approximately equimolecular proportions of the reactants can be used and the mixture preferably heated at from about 100 degrees to 150 degrees centigrade for from about 5 to about 60 minutes. The N-(3,3-dialkoxy-2-hydroxypropyl)-N-(arylsulfonyl)-p-aminobenzoate compound formed can be isolated from the reaction mixture, e. g. by washing the crude reaction product thoroughly with a suitable solvent, such as naphtha or isopropanol, to remove the catalyst and unreacted starting materials. Some of the N-(3,3-dialkoxy-2-hydroxypropyl)-N-(arylsulfonyl)-p-aminobenzoate esters are thus obtained as crystalline compounds having well defined melting points and some as sirupy liquids. They can be hydrolyzed to the corresponding acids by mixing with aqueous alkalies or other conventional hydrolytic agents and acidifying the aqueous reaction mixture, preferably with a mineral acid. Certain of the acids are thus obtained as solid substances.

New compounds represented by the generic formula (III) which can be prepared by the method herein described include, among many others: ethyl N-(3,3-dimethoxy-2-hydroxypropyl)-N-(benzenesulfonyl)-p-aminobenzoate, n-hexyl N-(3,3-di-n-propoxy-2-hydroxypropyl)-N-(o-toluenesulfonyl)-p-aminobenzoate, n-butyl N-(3,3-di-n-butoxy-2-hydroxypropyl)-N-(p-

chlorobenzenesulfonyl)-p-aminobenzoate, diethyl N'-(N-(3,3-dimethoxy-2-hydroxypropyl)-N-(benzenesulfonyl)-p-aminobenzoyl)-glutamate, di-n-hexyl N'-(N-(3,3-di-n-propoxy-2-hydroxypropyl)-N-(o-toluenesulfonyl)-p-aminobenzoyl)-glutamate, di-n-butyl N'-(N-(3,3-di-iso-butoxy-2-hydroxypropyl)-N-(p-bromobenzenesulfonyl)-p-aminobenzoyl)-glutamate, N-(3,3-dimethoxy-2-hydroxypropyl)-N-(benzenesulfonyl)-p-aminobenzoic acid, N-(3,3-di-n-butoxy-2-hydroxypropyl)-N-(o-toluenesulfonyl)-p-aminobenzoic acid, N-(3,3-di-n-butoxy-2-hydroxypropyl)-N-(p-chlorobenzenesulfonyl)-p-aminobenzoic acid, N'-(N-(3,3-dimethoxy-2-hydroxypropyl)-N-(benzenesulfonyl)-p-aminobenzoyl)-glutamic acid, N'-(N-(3,3-di-n-butoxy-2-hydroxypropyl)-N-(o-toluenesulfonyl)-p-aminobenzoyl)-glutamic acid, and N'-(N-(3,3-di-iso-butoxy-2-hydroxypropyl)-N-(p-bromobenzenesulfonyl)-p-aminobenzoyl)-glutamic acid.

Certain advantages of the invention are apparent from the following examples which are given by way of illustration only and are not to be construed as limiting.

Example 1.—Ethyl N-(3,3-diethoxy-2-hydroxypropyl)-N-(p-toluenesulfonyl)-p-aminobenzoate

A mixture of one gram of the diethyl acetal of 2,3-oxidopropanal, 1.5 grams of ethyl N-(p-toluenesulfonyl)-p-aminobenzoate and two drops of pyridine was heated for twelve minutes at 130° to 135° C. The clear melt which was formed was cooled and seeded with crystals of previously prepared ethyl N-(3,3-diethoxy-2-hydroxypropyl)-N-(p-toluenesulfonyl)-p-aminobenzoate. The partially crystalline mass was triturated with a mixture of six milliliters of petroleum naphtha and three milliliters of isopropanol and the mixture filtered. There was thus obtained 1.71 grams of ethyl N-(3,3-diethoxy-2-hydroxypropyl)-N-(p-toluenesulfonyl)-p-aminobenzoate melting at 89° to 94° C. Repeated recrystallization of the product from isopropanol-petroleum naphtha raised the melting point to 91° to 94° C.

Following substantially the same procedure, but using an equi-molar proportion of the dimethyl acetal of 2,3-oxidopropanal, the di-n-propyl acetal of 2,3-oxidopropanal, the di-n-butyl acetal of 2,3-oxidopropanal, the di-iso-butyl acetal of 2,3-oxidopropanal or of the di-dodecyl acetal of 2,3-oxidopropanal in place of the diethyl acetal of 2,3-oxidopropanal, there are formed ethyl N-(3,3-dimethoxy-2-hydroxypropyl)-N-(p-toluenesulfonyl)-p-aminobenzoate, ethyl N-(3,3-di-n-propoxy-2-hydroxypropyl)-N-(p-toluenesulfonyl)-p-aminobenzoate, ethyl N-(3,3-di-iso-butoxy-2-hydroxypropyl)-N-(p-toluenesulfonyl)-p-aminobenzoate, and ethyl N-(3,3-di-dodecyloxy-2-hydroxypropyl)-N-(p-toluenesulfonyl)-p-aminobenzoate, respectively.

Following substantially the same procedure, but using equi-molar proportions of ethyl N-(benzenesulfonyl)-p-aminobenzoate, n-hexyl N-(p-toluenesulfonyl)-p-aminobenzoate, n-butyl N-(p-chlorobenzenesulfonyl)-p-aminobenzoate, or of n-dodecyl N-(beta-naphthalenesulfonyl)-p-aminobenzoate in place of the ethyl N-(p-toluenesulfonyl)-p-aminobenzo-

ate, there are obtained ethyl N-(3,3-diethoxy-2-hydroxypropyl)-N-(benzenesulfonyl)-p-aminobenzoate, n-hexyl N-(3,3-diethoxy-2-hydroxypropyl)-N-(o-toluenesulfonyl)-p-aminobenzoate, n-butyl N-(3,3-diethoxy-2-hydroxypropyl)-N-(p-chlorobenzenesulfonyl)-p-aminobenzoate, and n-dodecyl N-(3,3-diethoxy-2-hydroxypropyl)-N-(beta-naphthalenesulfonyl)-p-aminobenzoate, respectively.

Example 2.—Diethyl N'-(N-(p-toluenesulfonyl)-p-aminobenzoyl)-1-glutamate

Thirty and nine-tenths grams of N-(p-toluenesulfonyl)-p-aminobenzoyl chloride and 23.9 grams of diethyl 1(+)-glutamate hydrochloride were dissolved in 300 milliliters of ethylene dichloride and the solution cooled to between 0° and 10° C. The cold solution was stirred vigorously and 22.3 grams of triethylamine in 72 milliliters of ethylene dichloride was added slowly over a period of about 20 minutes. The temperature of the mixture was held between 10° and 20° C. during the addition of the triethylamine and the mixture then allowed to stand at room temperature for one hour. The mixture was then washed successively with water, dilute hydrochloric acid, saturated aqueous sodium bicarbonate and finally with water. The colorless solution thus obtained was dried with anhydrous sodium sulfate and naphtha was added until the solution became opalescent. The mixture was then cooled to cause crystallization and filtered. The crystals, after drying, consisted of 36 grams of diethyl N'-(N-(p-toluenesulfonyl)-p-aminobenzoyl)-1-glutamate melting at 124° to 126° C.

Example 3.—Diethyl N'-(N-(3,3-diethoxy-2-hydroxypropyl)-N-(p-toluenesulfonyl)-p-aminobenzoyl)-1-glutamate

One and six-tenths grams of the diethyl acetal of 2,3-oxidopropanal and five drops of pyridine were added to 4.77 grams of fused diethyl N'-(N-(p-toluenesulfonyl)-p-aminobenzoyl)-1-glutamate at 140° C. The mixture was stirred for about 30 minutes at 145° to 150° C. The highly colored mass consisted chiefly of diethyl N'-(N-(3,3-diethoxy-2-hydroxypropyl)-N-(p-toluenesulfonyl)-p-aminobenzoyl)-1-glutamate. It had an index of refraction without further purification of $N_D^{20} = 1.527$.

Following substantially the same procedure, but using an equi-molar proportion of the dimethyl acetal of 2,3-oxidopropanal, the di-n-propyl acetal of 2,3-oxidopropanal, the di-n-butyl acetal of 2,3-oxidopropanal, the di-iso-butyl acetal of 2,3-oxidopropanal or the di-dodecyl acetal of 2,3-oxidopropanal in place of the diethyl acetal of 2,3-oxidopropanal, there are obtained diethyl N'-(N-(3,3-dimethoxy-2-hydroxypropyl)-N-(p-toluenesulfonyl)-p-aminobenzoyl)-1-glutamate, diethyl N'-(N-(3,3-di-n-propoxy-2-hydroxypropyl)-N-(p-toluenesulfonyl)-p-aminobenzoyl)-1-glutamate, diethyl N'-(N-(3,3-di-iso-butoxy-2-hydroxypropyl)-N-(p-toluenesulfonyl)-p-aminobenzoyl)-1-glutamate, diethyl N'-(N-(3,3-di-dodecyloxy-2-hydroxypropyl)-N-(p-toluenesulfonyl)-p-aminobenzoyl)-1-glutamate, respectively.

Following substantially the same procedure,

but using an equi-molar proportion of diethyl N'-(N-(benzenesulfonyl)-p-aminobenzoyl)-1-glutamate, di-n-hexyl N'-(N-(o-toluene-sulfonyl)-p-aminobenzoyl)-1-glutamate, di-n-butyl N'-(N-(p-chlorobenzenesulfonyl)-p-aminobenzoyl)-1-glutamate, or di-n-dodecyl N'-(N-(beta-naphthalenesulfonyl)-p-aminobenzoyl)-1-glutamate in place of diethyl N'-(N-(p-toluenesulfonyl)-p-aminobenzoyl)-1-glutamate, there are obtained diethyl N'-(N-(3,3-diethoxy-2-hydroxypropyl)-N-(benzenesulfonyl)-p-aminobenzoyl)-1-glutamate, di-n-hexyl N'-(N-(3,3-diethoxy-2-hydroxypropyl)-N-(o-toluene-sulfonyl)-p-aminobenzoyl)-1-glutamate, di-n-butyl N'-(N-(3,3-diethoxy-2-hydroxypropyl)-N-(p-chlorotoluenesulfonyl)-p-aminobenzoyl)-1-glutamate and di-n-dodecyl N'-(N-(3,3-diethoxy-2-hydroxypropyl)-N-(beta-naphthalenesulfonyl)-p-aminobenzoyl)-1-glutamate, respectively.

Example 4.—N-(3,3-diethoxy-2-hydroxypropyl)-N-(p-toluenesulfonyl)-p-aminobenzoic acid

A quantity of ethyl N-(3,3-diethoxy-2-hydroxypropyl)-N-(p-toluenesulfonyl)-p-aminobenzoate is warmed for several minutes

with slightly more than one molar portion of dilute aqueous or alcoholic sodium hydroxide and the mixture then cooled, diluted, acidified and filtered. There is thus obtained N-(3,3-diethoxy-2-hydroxypropyl)-N-(p-toluenesulfonyl)-p-aminobenzoic acid.

Following substantially the same procedure ethyl N-(3,3-dimethoxy-2-hydroxypropyl)-N-(p-toluenesulfonyl)-p-aminobenzoate, ethyl N-(3,3-di-n-propoxy-2-hydroxypropyl)-N-(p-toluenesulfonyl)-p-aminobenzoate, ethyl N-(3,3-di-n-butoxy-2-hydroxypropyl)-N-(p-toluenesulfonyl)-p-aminobenzoate, ethyl N-(3,3-di-iso-butoxy-2-hydroxypropyl)-N-(p-toluenesulfonyl)-p-aminobenzoate, butyl N-(3,3-di-dodecyloxy-2-hydroxypropyl)-N-(p-toluenesulfonyl)-p-aminobenzoate, n-hexyl N-(3,3-diethoxy-2-hydroxypropyl)-N-(o-toluenesulfonyl)-p-aminobenzoate, n-dodecyl N-(3,3-diethoxy-2-hydroxypropyl)-N-(beta-naphthalenesulfonyl)-p-aminobenzoate, diethyl N'-(N-(3,3-diethoxy-2-hydroxypropyl)-N-(p-toluenesulfonyl)-p-aminobenzoyl)-1-glutamate, di-n-butyl N'-(N-(3,3-diethoxy-2-hydroxypropyl)-N-(p-chlorobenzenesulfonyl)-p-aminobenzoyl)-1-glutamate, diethyl N'-(N-(3,3-diethoxy-2-hydroxypropyl)-N-(benzenesulfonyl)-p-aminobenzoyl)-1-glutamate and di-n-dodecyl N'-(N-(beta-naphthalenesulfonyl)-p-aminobenzoyl)-1-glutamate, respectively.

N-(3,3-dimethoxy-2-hydroxypropyl)-N-(p-toluenesulfonyl)-p-aminobenzoate, di-n-propoxy N-(3,3-diethoxy-2-hydroxypropyl)-N-(p-toluenesulfonyl)-p-aminobenzoate, di-n-butoxy N-(3,3-diethoxy-2-hydroxypropyl)-N-(p-toluenesulfonyl)-p-aminobenzoate, di-iso-butoxy N-(3,3-diethoxy-2-hydroxypropyl)-N-(p-toluenesulfonyl)-p-aminobenzoate, di-dodecyloxy N-(3,3-diethoxy-2-hydroxypropyl)-N-(p-toluenesulfonyl)-p-aminobenzoate, dihexyl N-(3,3-diethoxy-2-hydroxypropyl)-N-(o-toluenesulfonyl)-p-aminobenzoate, di-n-dodecyl N-(3,3-diethoxy-2-hydroxypropyl)-N-(beta-naphthalenesulfonyl)-p-aminobenzoate, diethyl N'-(N-(3,3-diethoxy-2-hydroxypropyl)-N-(p-toluenesulfonyl)-p-aminobenzoyl)-1-glutamate, di-n-butyl N'-(N-(3,3-diethoxy-2-hydroxypropyl)-N-(p-chlorobenzenesulfonyl)-p-aminobenzoyl)-1-glutamate, diethyl N'-(N-(3,3-diethoxy-2-hydroxypropyl)-N-(benzenesulfonyl)-p-aminobenzoyl)-1-glutamate and di-n-dodecyl N'-(N-(beta-naphthalenesulfonyl)-p-aminobenzoyl)-1-glutamate, respectively.

N-(3,3-di-iso-butoxy-2-hydroxypropyl)-N-(p-toluenesulfonyl)-p-aminobenzoic acid, N-(3,3-di-dodecyloxy-2-hydroxypropyl)-N-(p-toluenesulfonyl)-p-aminobenzoic acid, N-(3,3-diethoxy-2-hydroxypropyl)-N-(o-toluenesulfonyl)-p-aminobenzoic acid, N-(3,3-diethoxy-2-hydroxypropyl)-N-(beta-naphthalenesulfonyl)-p-aminobenzoic acid, N-(3,3-diethoxy-2-hydroxypropyl)-N-(p-toluenesulfonyl)-p-aminobenzoyl)-1-glutamic acid, N-(3,3-diethoxy-2-hydroxypropyl)-N-(p-chlorobenzenesulfonyl)-p-aminobenzoyl)-1-glutamic acid, N-(3,3-diethoxy-2-hydroxypropyl)-N-(benzenesulfonyl)-p-aminobenzoyl)-1-glutamic acid, and N-(3,3-diethoxy-2-hydroxypropyl)-N-(beta-naphthalenesulfonyl)-p-aminobenzoyl)-1-glutamic acid, respectively.

It is to be understood that the invention is not to be limited to the exact details of operation or exact compounds shown and described, as obvious modifications and equivalents will be apparent to one skilled in the art, and the invention is, therefore, to be limited only by the scope of the appended claims.

We claim:

1. A compound having the formula

wherein R' is a member of the group consisting of hydrogen and the alkyl radicals and n is a member of the group consisting of zero and the positive integer 1.

2. A compound as claimed in claim 1 wherein the alkyl radicals each contains less than 8 carbon atoms.

3. A compound as claimed in claim 1 wherein R' is an alkyl radical and n is the positive integer 1.

4. A compound as claimed in claim 1 wherein the arylsulfonyl radical is the p-toluenesulfonyl radical.

5. Ethyl N-(3,3-diethoxy-2-hydroxypropyl)-N-(p-toluenesulfonyl)-p-aminobenzoate.

6. Diethyl N'-(N-(3,3-diethoxy-2-hydroxypropyl)-N-(p-toluenesulfonyl)-p-aminobenzoyl)-1-glutamate.

7. The method which includes: reacting a dialkyl acetal of 1,2-oxidopropanal with an ester having the formula

wherein n is a member of the group consisting of zero and the positive integer 1 to form an hydroxy ester having the formula

8. The method of claim 7 wherein the arylsulfonyl radical is the p-toluenesulfonyl radical.

9. The method of claim 7 wherein the dialkyl acetal of 1,2-oxidopropanal is reacted with an alkyl ester of N-(p-toluenesulfonyl)-p-aminobenzoic acid.

10. The method of claim 7 wherein the dialkyl acetal of 1,2-oxidopropanal is reacted with a dialkyl ester of N-(p-toluenesulfonyl)-p-aminobenzoyl-glutamic acid.

11. The method which includes: reacting a di-

alkyl acetal of 1,2-oxidopropanal with an ester having the formula

wherein n is a member of the group consisting of zero and the positive integer 1 to form an hydroxy ester having the formula

and hydrolyzing the hydroxy ester with an alkali to form an hydroxy acid having the formula

12. The method which includes: heating a mixture comprising the diethyl acetal of 2,3-oxido-

propanal and ethyl N-(p-toluenesulfonyl)-p-aminobenzoate to form therein ethyl N-(3,3-diethoxy - 2 - hydroxypropyl) - N-(p-toluenesulfonyl) - p-aminobenzoate.

13. The method which includes: heating a mixture comprising the diethyl acetal of 2,3-oxido-
propanal and diethyl N'-(N-(p-toluenesulfonyl) - p-aminobenzoyl) - glutamate to form therein diethyl N'-(N-(3,3-diethoxy-2-hydroxy-

propyl) - N-(p-toluenesulfonyl) - p-aminobenzoyl) - glutamate.
